OXIDATION OF BENZENE TO PHENOL WITH AN ORGANIC PROMOTER

Filed Nov. 30, 1944

UNITED STATES PATENT OFFICE

2,440,233

OXIDATION OF BENZENE TO PHENOL WITH
AN ORGANIC PROMOTER

Robert H. Krieble, Schenectady, N. Y., and William I. Denton, Woodbury, N. J., assignors to Socony-Vacuum Oil Company, Incorporated, a corporation of New York

Application November 30, 1944, Serial No. 565,928

7 Claims. (Cl. 260—621)

1

This application, which is a continuation-in-part of our now abandoned copending application Serial No. 395,016, filed May 24, 1941, has to do with the production of phenol by the oxidation of benzene and is more particularly concerned with that type of process wherein a reaction mixture consisting of benzene and oxygen or oxygen-containing gas such as air is passed through a reaction zone void of solid catalyst, under pressure and at elevated temperature.

We are aware of the fact that processes of this general character have heretofore been proposed, and in this regard reference is made to the Bone et al. Patent No. 2,199,585 and the Moyer et al. Patent No. 2,223,383. Each of these patents discloses a process of the general character above referred to, and each mentions that the process therein disclosed can be carried out by recycling. We have discovered, however, that although the process of Bone, for example, if used with a relatively impure grade of commercial benzene, can be operated to obtain a fair yield of phenol on a small number of passes in a recycling operation, the conversion to phenol rapidly decreases with successive cycles, thus materially restricting the scope of the process and rendering it impractical as a recycle operation. We have also observed that if a chemically pure (reagent grade) of benzene is subjected to the process of the Bone patent, no substantial conversion to phenol is obtained.

Since the percentage conversion of benzene to phenol in an oxidation process of the class described is relatively small, it is obviously essential from the standpoint of practicability that the operation be one in which the unconverted benzene can be continuously recycled with a substantially constant conversion and yield of phenol under a given set of operating conditions. It is the primary object of this invention to provide such a process.

This invention is predicated upon the discovery that if a minor proportion of a compound which under the conditions of reaction in the process is a better hydrogen donor than benzene—cyclohexane or cyclohexanol, for example—is continuously introduced into the stream of benzene entering the reaction mixture, the conversion and yield of phenol is substantially improved over the conversion and yield obtained without the hydrogen donor and, further, that the conversion and yield will remain substantially constant in a continuous operation for a given set of operating conditions.

For the continuous operation contemplated

2

herein a properly proportioned mixture of benzene and oxygen, air or other oxygen-containing gas (one containing oxygen in admixture with one or more other gases), is thoroughly mixed and pre-heated to the desired temperature and passed through a reactor tube which has been pre-heated and which for the purpose of pre-heating and dissipating the heat of the exothermic reaction is immersed in a suitable heat-transfer bath such as salt. The reaction mixture, as will hereinafter be explained, is preferably maintained under pressure. With properly regulated conditions a part of the benzene is thus oxidized to phenol. This phenol and the gaseous and high-boiling products of oxidation are then separated from the benzene, which is subsequently recycled through the mixer-preheater and reactor. Additional oxygen, air or other oxygen-containing gas is of course added prior to the admission of the benzene to the pre-heater-mixer, and in a continuous operation make-up benzene is also added to replace the benzene converted.

In such an operation we have found that where a commercial grade of benzene, such as "90% Benzol," is used as the charging stock and is recycled through the reactor with no additions of make-up stock under fixed conditions of temperature and pressure, the benzene rapidly loses its reactivity and, further, that the reactivity may be restored only in part through altering the reacting conditions by going to higher temperatures. The charge eventually becomes unreactive even at relatively high temperatures. We have also found that when the procedure just described above is altered by adding fresh make-up benzene, the reactivity and conversion to phenol is not markedly increased. However, in an operation of the recycle type just described, if a minor proportion of cyclohexane is continuously added to the charge of benzene, a steady conversion performance may be obtained and the reactivity, as indicated by the per cent conversion and yield of phenol at a given temperature, is greatly increased. We have found that the reactivity in a process of the class described under a given set of conditions may be greatly increased by the incorporation in the reaction mixture of a minor proportion of cyclohexane. For example, under a given set of conditions recycle stock with 6 per cent make-up fresh benzol gave a conversion to phenol of only 0.1 per cent of the total charge, while the same recycle stock with about 1 per cent of cyclohexane gave a conversion of 2 per cent by weight of phenol under the same conditions.

Although we do not wish to be bound by any theory as to the mechanism of this reaction or the part which the cyclohexane or other inductor or promoter plays in increasing the reactivity and conversion to phenol, it is our view that the mechanism as represented by the following equations will explain most of the observed facts:

Reaction I is slow and determines the rate. Reactions II and III, since they involve radicals, should be extremely rapid. Reaction III is shown as a competition of phenyl and hydroxyl radicals for phenyl and is probably over-simplified. The essential fact is that in the presence of a material which can be more readily dehydrogenated by O_2 than benzene, HO_2 is produced independently of reaction I and at a lower temperature. It is then capable of reacting rapidly with benzene by reactions II and III to produce the usual products.

Under these conditions, far more phenol survives, less diphenyl is formed, and the yield is greatly improved.

According to the foregoing mechanism, then, an inductor or promoter for use in a process of the type contemplated herein is any compound which is a better hydrogen donor than benzene under the conditions of the reaction zone; or, stated in another way, a promoter or inductor may be defined as a compound containing hydrogen and possessing the properties of being in the gaseous phase under the conditions of the reaction zone and, under said conditions, reacting with oxygen to form water at a lower temperature than the temperature at which benzene so reacts with oxygen.

Cyclohexane is a preferred compound for use as an inductor in this process, first, for the reason that it is highly effective in promoting the conversion to phenol and, second, for the reason that it is converted to benzene in the reaction of the process and thereby avoids any problem of contamination. It is to be understood, however, that the process contemplated herein is not limited to cyclohexane as the promoter or inductor but broadly comprehends any compound which under the conditions of the reaction zone is a better hydrogen donor than benzene. For example, such a compound may be obtained in the reaction mixture by partially hydrogenating the benzene. This can be conveniently accomplished, as will hereinafter appear, by passing the benzene charge through a hydrogenation chamber containing a suitable catalyst and adding hydrogen to the chamber at a metered rate in a quantity to effect the desired amount of hydrogenation. Other promoting compounds and materials which we have tested and found to be effective in increasing the conversion and yield in a process of the class described are: cyclohexanol, cyclohexanone, cyclohexane, tetra-hydro naphthalene, 2-ethyl-3-propyl acrolein, octaldehyde, n-hexane, diethyl ether, aniline, turpentine, n-hexene, and cracked gasoline. Each of the aforesaid promoting compounds and materials are char- 75

acterized by the elements carbon and hydrogen, and several are further characterized by oxygen or nitrogen. Cyclohexanol was found to be particularly effective in promoting the reaction; and although this compound may present the same advantages as cyclohexane from the standpoint of noncontamination, it is not so desirable from an economical standpoint because of its present high cost. As classes of compounds contemplated herein for use as promoters or inductors, preference is given to the hydrogenated aromatic hydrocarbons typified by cyclohexane, cyclohexene, tetra-hydro naphthalene, etc., and the olefins, which are typified by n-hexene and cracked gasoline.

As stated hereinabove, the promoters contemplated by the present invention are better hydrogen donors than benzene under the conditions of the reaction zone. In other words, the promoters in our process are hydrogen-containing materials which release hydrogen more readily than benzene under the conditions of reaction. The rates of hydrogen release from numerous materials are available in the chemical literature and may be resorted to in selecting effective promoting materials. From such data we have derived "potential hydrogen donor ability" (P. H. D. A.) values for various materials and have found those materials having values above a certain minimum are effective in our process. The P. H. D. A. value relationship thus provides a means whereby a chemist skilled in the art may readily determine, with a high degree of certainty, whether or not a material will be an effective promoter.

The P. H. D. A. values obtained for various materials are derived in the following manner. Hydrogen atoms are classified here into four categories: primary, secondary, tertiary and hydrogens attached to an olefinic bond or an aromatic ring. No attempt has been made to evaluate bonds other than the carbonhydrogen bond. With this as a starting point and taking activation energy values from the chemical literature, it is possible to evaluate relative ratios of release of the different hydrogen atoms from hydrogen-containing materials. Average activation energy values taken from "The Aliphatic Free Radicals" (F. O. Rice and O. K. Rice, Johns Hopkins Press; 50 1935) are as follows:

Type of Hydrogen Atom	Average Activation Energy, Kilocalories	Difference in Activation Energy
55		
Olefinic (Aromatic)	103	0
Primary	97	6
Secondary	95.5	7.5
Tertiary	93.3	10

Relative rates of hydrogen release under conditions typical of our process, as at 427° C., are calculated from the well-known relationship [Arrhenius' equation (Getman and Daniels: *Outlines of Theoretical Chemistry*, 5th ed., pages 336 and 344, John Wiley & Sons, Inc., N. Y.)].

$$K = C e^{-\frac{E}{RT}}$$

wherein K is the specific velocity constant; C is a constant; E represents activation energy (in calories); R is a constant (1.987 calories); and T is absolute temperature (in degrees Kelvin).
5 The relative rate of a primary hydrogen atom as

compared with an olefinic hydrogen atom is calculated as follows:

$$K_{47^\circ C} = e^{\frac{6000}{2(427+273)}}$$

$$\log K_{47^\circ C} = 1.864$$

$$K_{47^\circ C} = 73$$

In this manner it is found that the several hydrogen atoms have the following K values at 10 427° C.

Olefinic (aromatic) -----	1
Primary -----	73
Secondary -----	215
Tertiary -----	1,280

The foregoing $K_{47^\circ C}$ values indicate that a primary hydrogen atom is released 73 times faster than an olefinic or aromatic hydrogen atom. Simplifying this relationship by assigning a zero (0) value to an olefinic or aromatic hydrogen atom and a value of one (1) to a primary hydrogen atom, the following values obtain:

Olefinic (aromatic) -----	0
Primary -----	1
Secondary -----	3
Tertiary -----	15

It will be recognized that the foregoing values have been assigned to the so-called normal hydrogen atoms. Hydrogen atoms attached to carbon atoms which are in the alpha position to an olefinic bond or some electronegative group such as keto ($>C=O$), ether ($—O—$) or ester ($—COOR$) are released from the molecule at an increased rate. It is difficult to evaluate this effect since it depends largely upon the structure of the molecule. It is recognized that different substituent groups such as olefin, ketone, ester, ether, etc., groups may activate hydrogen atoms to different degrees. For convenience, however, a constant value has been assigned to such activation. According to, whenever a primary hydrogen is in an activated position, it is assigned a value equivalent to a normal secondary hydrogen. Similarly, an activated secondary hydrogen atom is assigned a value equivalent to a normal tertiary hydrogen atom; and for an activated tertiary hydrogen atom, the normal rate is doubled. The P. H. D. A. of a compound, on a weight basis, is the sum of all the evaluated hydrogen atoms multiplied by a factor of ten and divided by the molecular weight of the compound.

From the $K_{47^\circ C}$ values of 0, 1, 3 and 15 shown above, the P. H. D. A. values of hydrogen-containing materials are easily calculated. By way of illustration, cyclohexane has twelve secondary hydrogen atoms and, therefore, has a P. H. D. A. value, on a weight basis, of

$$4.4 \left(\text{from } \frac{12 \times 3 \times 10}{84} \right)$$

Illustrative of materials found to be ineffective experimentally and so indicated by its P. H. D. A. value is ethyl alcohol. This compound has three primary and two secondary hydrogen atoms, and has a P. H. D. A. value, on a weight basis, of 2.0.

The P. H. D. A. values for materials tried in our process as promoters are in substantial agreement with the experimental results obtained. However, in the case of first members of the various chemical classes which often behave differently than all other members of their classes, some discrepancies obtain between the P. H. D. A.

values and the experimental results. In general, then, those materials which have P. H. D. A. values, on a weight basis, of from 0 to about 2.5 are ineffective, and those which have values 5 greater than about 2.5 are effective; however, those having values greater than 4 are generally characterized by a high degree of effectiveness. This relationship is shown in the following tabulation:

Compound	P. H. D. A. (Weight)
carbon disulfide	0
thiophene	0
pyridine	0
ethyl alcohol	2.0
acetone	2.0
toluene	1.0
xylene	1.7
isopentane	4.2
n-hexane	3.5
n-hexene-1	5.4
cyclohexane	4.4
cyclohexene	8.8
cyclohexanol	5.4
cyclohexanone	8.0
tetralin	5.5
ethyl ether	9.0
2-ethyl, 3-propyl acrolein	8.0
turpentine (taken as α -pinene)	8.9
ethyl xanthic disulfide	2.7

As will be readily apparent to those skilled in the art, the apparatus used in carrying out a process of the type contemplated herein may take various forms. In the accompanying drawings, however, we have shown diagrammatically one form of apparatus which may be satisfactorily used in carrying out an operation for the continuous conversion of benzene to phenol. As will hereinafter appear, the conditions of operation embody a number of variables which may be changed with respect to one another over relatively wide limits, and no attempt will be made in describing the apparatus to take account of these possible changes in variables.

Referring now to the drawing, reference numerals 11 and 11' indicate conduits which carry benzene and are connected through suitable 45 valves 12 and 12' with the inlet 13 of a pump 14. The pump 14 delivers the benzene through a conduit 15 to a T-connection 16, where it is introduced into a mixing conduit 17 leading to the coils 18 of a mixer and pre-heater mounted in an insulated case 19 which is filled with a suitable heat-exchange medium.

Reference numeral 20 indicates an air-compressor which discharges into pipe 21 connected through the connection 22 to a compressed-air storage reservoir 23. The pipe 21 discharges through a pressure-reducing valve 24 and an orifice flow-control 25 into the conduit 17, through which the air-and-benzene reaction mixture is conducted to the mixing and pre-heating coil 18. The inductor or promoter is introduced into the reaction mixture at any suitable point, preferably in the benzene stream, through a conduit as indicated by numeral 26, such conduit being provided with a metering 60 valve 29 to control the quantity of an inductor, such as cyclohexane, which is introduced.

As was previously pointed out, the inductor or promoting compound may be formed by hydrogenating a portion of the benzene prior to its introduction through the reaction zone, and means 70 for carrying out this alternative procedure may be embodied in an apparatus of the type illustrated by placing a valve 30 in the benzene conduit 15 and providing a connection 31 on the up-stream side of the valve 30 through which a

part or all of the benzene stream can be conducted into a hydrogenation chamber 32, which discharges the partially hydrogenated benzene through the pipe 33 into the conduit 15 on the down-stream side of the valve 30.

The pipes 31 and 33 are shown as being provided with control-valves 31' and 33'. The hydrogenation chamber, as aforesaid, contains a suitable hydrogenation catalyst such as nickel and is maintained in any suitable manner at an elevated temperature of from about 250° F. to 400° F. Hydrogen is introduced through pipe 31 provided with a meter 38.

The pre-heating and mixing coil 18, wherein the benzene-promoter-air mixture is intimately mixed and pre-heated to a temperature below the temperature at which reaction will take place, discharges into a header 40, which connects with a series of reactor tubes 41. The reactor tubes are suspended in a suitable heat-transfer bath, such as a fused salt bath, capable of maintaining a close temperature control, such bath being contained in the insulated case 42, which is provided with an inlet conduit 43 having a pump 44 the inlet 45 of which connects with a heat-exchanger 46 which can be used to raise the temperature of the salt bath for initiating the reaction and, after the exothermic reaction has started, can be used to dissipate the heat of reaction and maintain a constant temperature. The heat-exchanger 46 receives the heat-exchange medium from the tank 42 through a discharge conduit 47.

In the form of the apparatus shown in the drawing, the reactor tubes are illustrated as being U-shaped, and the discharge portion 41' of the respective reactor tubes connect with a header conduit 50 which discharge into the coil 51 of a heat-exchanger 52. For the thermal balance of the process this heat-exchanger 52 is shown as being connected through conduits 53 and 54 with the mixer and pre-heater 19 so that the heat-exchange medium is circulated by means of pump 55 from the bottom of the mixer and pre-heater 19 to the bottom of the heat-exchanger 52 and back to the mixer and pre-heater through the pipe 53.

The cooled reaction mixture containing the phenol and other products of the reaction discharges from the heat-exchanger 52 through pipe 56-58 and filter 57 into a high-pressure mist-breaking tower 58 having a high-pressure gas-discharge valve 59 which may lead to a turbine. Discharge valve 59 is controlled by orifice flow-control 26 to maintain a constant flow of air in pipe 17. The liquid product accumulating in the bottom of the high-pressure tower 58 is conducted through a pressure-reducing valve 60 into a low-pressure-packed tower 61 provided with a valved vent 62 to release gaseous products. The liquid product collecting in the bottom of tower 61 is discharged through conduit 61'. This liquid product, which is a mixture of phenol, benzene, and "high-boilers," is delivered to the benzene-recovery still 62. In the still as illustrated the liquid products pass through a pre-heater 63 and are discharged through the discharge pipe 63' into the bottom of the still 62, where the benzene is distilled off by a steam coil reboiler 64. The still 62 is shown as being equipped with bubble plates 65 and a water coil reflux-condenser 65'. The benzene vapors are discharged through conduit 66 into a benzene condenser 66', from which the liquid product discharged through conduit 67 is pumped by means of pump 68 into a benzene-washing tower 75

88, from which the recycle benzene enters the benzene conduit 11'.

The bottom of the benzene-recovery still 62 is provided with a discharge conduit 78 through which the mixture of phenol and high-boilers is pumped into a vacuum still 71, wherein the phenol is distilled off by means of the steam reboiler coil 72 into the phenol-discharge conduit 73, which connects with the phenol condenser 74 10 from which the condensed phenol is discharged through the conduit 75 into a receiver 16 provided with a valved vacuum line 17 and a valved phenol-discharge pipe 78 connected with a phenol-discharge pump 79. The high-boiling products of 15 oxidation, which are referred to as "high-boilers," are discharged from the still 71 through the conduit 88 by means of a pump 81.

As has been previously pointed out, the process contemplated herein embodies a number of 20 variables which are susceptible of adjustment with respect to one another to obtain optimum operating conditions for a given set of variables. These variables include: the ratio of oxygen and benzene in the reaction mixture; the reaction 25 time; the pressure under which the operation is carried out; the temperature of reaction; the material, internal diameter, and length of the reactor tube; the internal diameter and length of the pre-heater coil and the temperature of 30 the pre-heater bath; and the material used as the inductor and the proportions in which it is used.

In order that some indication may be afforded as to the effect of these variables, each of them 35 will now be discussed individually.

Reaction mixture

The proportion of air that can be used to advantage in the reaction mixture has an upper 40 practicable limit that varies with the conditions used and particularly with the internal diameter of the reactor tube (41-41').

In tubes having an internal diameter of from .2 inch to .35 inch operating at a pressure of 1000 pounds per square inch, good yields of phenol are readily obtainable with mixtures which are not richer in oxygen than a mixture containing 4 mols of benzene to 1 mol of oxygen and 4 mols of nitrogen. Mixtures of higher oxygen content result in a greatly increased production of "high-boilers," which greatly lowers the yield of phenol even though the conversion to phenol may be moderately greater. Also, good yields of phenol have been obtained in reactor tubes of this size with mixtures in the ratio of 2 mols of benzene to 1 mol of oxygen and 4 mols of nitrogen by keeping the reactor bath temperature low enough to permit the consumption of only half of the oxygen, but this requires very accurate temperature control and presents no advantage either in conversion or in yield of phenol over the use of the 4:1:4 mixture first referred to. Under the conditions just described we prefer to use mixtures of from 8 to 4 molecular proportions of benzene to 1 molecular proportion of oxygen.

With a smaller reactor tube having an internal diameter of say .086 inch, the situation is somewhat different. In a tube as small as this the reaction is very much less temperature-sensitive, making it a relatively simple matter to control the bath temperature in such a way that only a part of the oxygen in the mixture is consumed. With this tube the best results have been obtained with the mixture $2C_6H_6 + O_2 + 4N_2$ at temperatures where from $\frac{1}{4}$ to $\frac{1}{2}$ of the available

oxygen is consumed. Under these conditions a higher yield of phenol is obtained than with the mixture $8C_6H_6 + O_2 + 4N_2$ although the conversions to phenol are not greatly changed.

With a small tube of this character higher pressures in the neighborhood of from 2000 to 3000 pounds per square inch are also desirable.

Reaction time

For the purpose of this discussion the reaction time may be defined as the time taken for a molecule of the reactant mixture to pass through the reactor tube under operating conditions. The reaction time is not an important variable provided it exceeds a certain minimum value which varies with the apparatus and the conditions of use. Above this so-called critical minimum value an increase in reaction time can be compensated for by a small decrease in reaction temperature. However, for reaction times below the minimum value there is a sharp rise in the production of high-boilers and a corresponding decline in phenol yield although the actual conversion to phenol is not greatly affected. The value of this so-called critical minimum reaction time, as aforesaid, is dependent upon the apparatus and conditions of use, and it is probable that the controlling factor rests in the ability of the apparatus to dissipate heat. The critical minimum reaction time is about 10 seconds under the following conditions:

Charge: Baker's reagent benzene + 1% cyclohexane.
 Reactor: .35 inch internal diameter stainless steel tube 15' long.
 Mixture: $8C_6H_6 + O_2 + 4N_2$.
 Pressure: 1000 pounds per square inch.

If the reaction time is between 13 and 140 seconds, the optimum reaction temperature lies between 700° F. and 750° F., the conversion to phenol between 2 and 3 per cent, and the yield of phenol from 55 to 65 per cent.

The critical minimum reaction time is about 2 seconds under the following conditions:

Charge: "1° thiophene-free benzene" (containing 1% cyclohexane).
 Reactor: .086 inch internal diameter iron tube 15' long.
 Mixture: $2C_6H_6 + O_2 + 4N_2$.
 Pressure: 1000 pounds per square inch.

With a 2.3 second reaction time, phenol is produced in 3 per cent conversion and 50 per cent yield at 955° F. Better operation is obtained, if in the above conditions, the pressure is raised to 2000 pounds per square inch. Then phenol is produced in from 3 to 4 per cent conversion and from 60 to 65 per cent yield over a range of reaction times from 5 to 35 seconds. The optimum reaction temperatures are from 790° F. to 840° F.

Pressure

We have obtained phenol in good conversion at pressures of from 60 pounds per square inch to 3000 pounds per square inch. The higher the pressure, the lower the optimum reactor temperature, other conditions being the same. Thus, while at 60 pounds per square inch, temperatures of the order of 1200° F. are required, at 2000 pounds pressure good results have been obtained at 675° F. Since ferrous metal surfaces strongly catalyze total combustion at temperatures above 1000° F., it is necessary to use inert surfaces such as glass, enamel, silica, etc., in the reactor when

operating at low pressures and the concomitant high temperatures. In this connection, good results have been obtained in nickel tubes at a pressure of 350 pounds per square inch where the optimum reaction temperature was about 1030° F., and probably still lower pressures and higher temperatures could have been successfully used. With iron tubes, sufficient pressure to keep the reaction temperature below 1000° F. is required usually at least 500-1000 pounds per square inch. However, at 1000 pounds pressure, the use of nickel tubes instead of iron or stainless steel tubes presents no advantage.

The use of high pressure has certain fundamental advantages, however. At low pressures, even though a glass-lined reactor be used, the loss to oxides of carbon is materially higher than at high pressures in stainless steel equipment. Furthermore, the minimum critical reaction time apparently increases with decreasing pressure; and, since for a constant reaction time the rate of feed varies directly with the pressure (by definition), the maximum permissible rate of throughput falls off very rapidly with decreasing pressure.

There is also an upper useful limit of pressure. As the pressure is raised, the temperature required to initiate reaction decreases, as explained above. Furthermore, the boiling point of benzene is raised until the critical temperature of liquid benzene (550° F.) is reached, where it remains unchanged as the pressure is further increased. Since it is advantageous to mix thoroughly the benzene vapor and air before initiating reaction, in order that local regions of undesirably high oxygen-concentration be eliminated, it is not desirable to indefinitely lower the reaction temperature by the use of extremely high pressures. There is a relationship between the maximum useful pressure and the internal diameter of the reactor tube, since we have found that the smaller the internal diameter of the reactor tube, the higher the temperature necessary to initiate reaction. Thus, pressures at least as high as 3000 pounds per square inch and probably higher, can be used to advantage in a .086 inch internal diameter reactor tube, while in a .35 inch internal diameter reactor tube 2000 pounds per square inch appears to be about the upper useful limit, and we prefer a pressure of 1000 pounds per square inch. Because of this same relationship between internal diameter and reaction temperature and the catalytic effect of the iron tube walls discussed above, a .086 inch internal diameter tube requires a pressure of at least 1000 pounds per square inch, while a .35 inch internal diameter tube has given fairly good results at 500 pounds per square inch.

Temperature

The optimum reaction temperature can be varied from 650-1225° F. by changing the operating conditions, among the most effective of which are pressure, inductor concentration and internal diameter of reactor tube. This is discussed in the sections entitled "Pressure" and "Inductor."

Reactor tube

As we have previously indicated, it is highly desirable that the reactor tube be void of solid catalyst and that it be of a material which will have no substantial catalyzing effect in accelerating the oxidation of benzene. We have observed in this connection that the chief effect of a solid catalyst is to increase the loss to total-combustion

products and therefore to be avoided in the reactor tube (41—41'). At the relatively high temperature encountered in low-pressure oxidation the use of extremely inert (non-catalytic) inner surfaces of the reactor tubes, such as glass, enamel, glazed porcelain, or silica, is imperative.

At moderate pressures (several hundred pounds per square inch) nickel is satisfactory. At pressures in the neighborhood of 1000 pounds per square inch low-carbon steel and stainless steel are satisfactory, and nickel presents no advantage.

As to the internal diameter of the reactor tube (41—41') successful operation has been obtained in tubes varying from .086 inch to .875 inch in internal diameter. For iron tubes, the smaller the internal diameter the higher the required pressure. We prefer to use a tube having an internal diameter in the neighborhood of .35 inch and to operate with pressures in the range of from 500 to 2000 pounds per square inch. Smaller tubes are equally satisfactory, but they require higher operating pressures. For a tube having an internal diameter of .086 inch, pressures of from 2000 pounds to 3000 pounds per square inch are recommended.

The length of the reactor tube (41—41') apparently determines the rate of throughput, and the existence of a critical minimum reaction time for a tube of fixed length and internal diameter has already been discussed. Satisfactory results in the operation of a process of the class described have been obtained with tube lengths of 15 feet, and tubes of at least this length are recommended.

Mixer-pre-heater tube

As to the mixer-pre-heater tube (18) any material having suitable mechanical properties such as stainless steel is satisfactory. The internal diameter of this tube should be sufficiently small to prevent reaction taking place therein, and the tube should be sufficiently long to provide the heating surface necessary for a heat-exchange that will maintain the feed temperature within 25° F. to 50° F. of the temperature of the pre-heater bath. The temperature of the pre-heater bath should be such that the reaction mixture discharged from the pre-heater coil 18 is at a temperature of about 50—150° F. below the temperature maintained in the reactor bath in the case 42.

Inductor

The required properties of the inductors and the theory of their action, together with certain preferences therein to cyclohexane and the like, have already been discussed.

The concentration of the inductor may be varied depending upon the character of the make-up stock, the conditions of operation, etc.; but we have found that this concentration should be maintained in the neighborhood of from about 0.2 per cent to about 3 per cent, by volume, based upon the quantity of benzene in the reaction mixture. We prefer to use a concentration of inductor in the neighborhood of from 0.5 per cent to 1 per cent, by volume, and have found that increasing the concentration of the inductor greatly lowers the optimum reaction temperature.

It will be seen from the foregoing discussion that a process of the type contemplated herein is susceptible of numerous operating conditions through manipulation of the variables discussed, and the present invention is not concerned with any particular set of operating conditions but, as aforesaid, is predicated upon the discovery 70

that greatly improved results and a continuous recycling operation may be obtained by introducing into the reaction mixture an inductor or promoting compound of the type hereinabove discussed. It is to be understood, therefore, that although we have described and illustrated a specific form of apparatus and have discussed in considerable detail various reaction conditions which may be employed in the operation of such apparatus, the invention is not limited to this apparatus or to any particular set of operating conditions but includes within its scope such changes and modifications as fairly come within the spirit of the appended claims.

15 We claim:

1. In the method of making phenol wherein a reaction mixture of benzene vapor and oxygen-containing gas is passed under a pressure in excess of about 500 pounds per square inch through a reaction zone at a temperature between about 650° F. and 1000° F., said reaction zone having a metallic surface and being void of solid catalyst, the step of incorporating in the reaction mixture a minor proportion, from about 0.2 per cent to about 3.0 per cent by volume based upon the quantity of benzene in the reaction mixture, of cyclohexane.

2. In a method for the continuous manufacture of phenol from benzene wherein a reaction mixture of benzene vapor and oxygen-containing gas is passed under a pressure in excess of about 500 pounds per square inch through a reaction zone at a temperature between about 650° F. and about 1000° F. to convert a part of the benzene to phenol and other oxidation products and wherein unconverted benzene is separated from the phenol and other oxidation products and is returned for recycling in the reaction mixture, said reaction zone having a metallic surface and being void of solid catalyst; the improvement which comprises continuously incorporating in the benzene so recycled, prior to its admission to the reaction zone, a minor proportion, from about 0.5 per cent to about 1.0 per cent by volume, of cyclohexane.

3. In a method for the continuous manufacture of phenol from benzene wherein a reaction mixture of benzene vapor and oxygen-containing gas is passed under a pressure in excess of about 500 pounds per square inch through a reaction zone at a temperature between about 650° F. and about 1000° F. to convert a part of the benzene to phenol and other oxidation products and wherein unconverted benzene is separated from the phenol and other oxidation products and is returned for recycling in the reaction mixture, said reaction zone having a metallic surface and being void of solid catalyst; the improvement which comprises continuously hydrogenating a minor proportion of the benzene so recycled prior to its admission to the reaction zone, thereby incorporating in the benzene a minor proportion, from about 0.2 per cent to about 3.0 per cent by volume, of hydrogenated benzene.

4. In the method of making phenol wherein a reaction mixture of benzene vapor and oxygen-containing gas is passed under a pressure in excess of about 500 pounds per square inch through a reaction zone at a temperature between about 650° F. and about 1000° F., said reaction zone having a metallic surface and being void of solid catalyst, the step of incorporating in the reaction mixture a minor proportion, from about 0.2 per cent to about 3.0 per cent by volume based

13

upon the quantity of benzene in the reaction mixture, of an organic compound selected from the group consisting of those consisting of carbon and hydrogen and those consisting of carbon, hydrogen, and oxygen, which compound is in the gaseous phase under the conditions of the reaction zone and which, under said conditions, is a better hydrogen donor than benzene and which has a "potential hydrogen donor ability" value greater than about 2.5.

5. In a method for the continuous manufacture of phenol from benzene wherein a reaction mixture of benzene vapor and oxygen-containing gas is passed under a pressure in excess of about 500 pounds per square inch through a reaction zone at a temperature between about 650° F. and about 1000° F. to convert a part of the benzene to phenol and other oxidation products and wherein unconverted benzene is separated from the phenol and other oxidation products and is returned for recycling in the reaction mixture, said reaction zone having a metallic surface and being void of solid catalyst; the improvement which comprises continuously incorporating in the benzene so recycled, prior to its admission to the reaction zone, a minor proportion, from about 0.2 per cent to about 3.0 per cent by volume, of an organic compound selected from the group consisting of those consisting of carbon and hydrogen and those consisting of carbon, hydrogen, and oxygen, which compound is in the gaseous phase under the conditions of the reaction zone and which, under said conditions, is a better hydrogen donor than benzene and which has a "potential hydrogen donor ability" value greater than about 2.5.

35 6. The continuous method for the manufacture of phenol from benzene which comprises: passing a reaction mixture of benzene and oxygen-containing gas through a reaction zone having a metallic surface and being void of solid catalyst, under a pressure in excess of about 500 pounds per square inch and at a temperature between about 650° F. and about 1000° F., said

14

benzene containing a minor proportion, from about 0.2 per cent to about 3.0 per cent by volume, of an organic compound selected from the group consisting of those consisting of carbon and hydrogen and those consisting of carbon, hydrogen, and oxygen, which compound is in the gaseous phase under the conditions of the reaction zone and which, under said conditions, is a better hydrogen donor than benzene and which has a "potential hydrogen donor ability" value greater than about 2.5; separating from the products of reaction unconverted benzene and phenol substantially free of unconverted benzene; recycling unconverted benzene with a quantity of fresh benzene sufficient to replace benzene converted in the previous passage through said reaction zone, and with oxygen-containing gas; and continuously incorporating with the recycle benzene charge, prior to its admission in said reaction zone, said minor proportion of said organic compound.

20 7. In the method of making phenol wherein a reaction mixture of benzene vapor and oxygen-containing gas is passed under a pressure in excess of about 500 pounds per square inch through a reaction zone at a temperature between about 650° F. and about 1000° F., said reaction zone having a metallic surface and being void of solid catalyst, the step of incorporating in the reaction mixture a minor proportion, from about 0.2 per cent to about 3.0 per cent by volume based upon the quantity of benzene in the reaction mixture, of cyclohexene.
